No. 823,169.

PATENTED JUNE 12, 1906.

W. E. HAZARD.
COVER FOR IRONING BOARDS.
APPLICATION FILED AUG. 23, 1905.

UNITED STATES PATENT OFFICE.

WILLIAM E. HAZARD, OF ST. LOUIS, MISSOURI.

COVER FOR IRONING-BOARDS.

No. 823,169.

Specification of Letters Patent.

Patented June 12, 1906.

Application filed August 23, 1905. Serial No. 275,436.

To all whom it may concern:

Be it known that I, WILLIAM E. HAZARD, a citizen of the United States, residing at St. Louis, in the State of Missouri, have invented 5 a new and useful Improvement in Covers for Ironing-Boards, of which the following is a specification.

My invention relates to an ironing-board cover and means for fastening the same to 10 the board, and has for its object to insure a tight and smooth surface to the cover over the entire top side of the board.

The invention consists in features of novelty, as hereinafter described and claimed, 15 reference being had to the accompanying drawings, forming part of this specification, whereon—

Figure 1 is a top plan of an ironing-board with its cover (broken away) secured thereto 20 according to my invention; Fig. 2, an inverted plan of the board, showing the lapped lateral portions of the cover united to each other at their edges before connecting the ends and tightening the cover to the board; 25 Fig. 3, a similar view to Fig. 2, showing the cover completely fastened and tightened throughout to the board; Fig. 4, an inverted plan of the board, omitting the cover; Fig. 5, a cross-section to enlarged scale through the 30 board and cover in their fastened position on line 5-5 in Figs. 1 and 3; Fig. 6, an inverted plan to enlarged scale of one of the double hooks or fasteners forming part of my invention and applied to a portion of the cover, as 35 seen in Figs. 2 and 3; and Fig. 7, a side view of the hook, as seen in Fig. 5, detached from the cover.

Like letters and numerals of reference denote like parts in all the figures.

40 *a* represents an ironing-board having a cover *b*, which is composed of cloth or other suitable fabric or material, the lateral and end portions 1 and 2, respectively, of the cover *b* passing over the corresponding edges 45 of the board *a* and underlapping the same, as shown in Figs. 2, 3, and 5. Through the cover *b* adjacent to its side edges and at suitable intervals along the same are formed eyelet-holes 3, and through each end portion 2 50 of the cover *b* is a similar eyelet-hole 3', (or more than one eyelet-hole 3' may be used, if desired.) In each eyelet-hole 3 3' is removably inserted one of two combined hooks or catches 4, (seen particularly in Figs. 6 and 7,) 55 which are arranged opposite to each other in the same plane at a suitable distance apart,

the shanks 5 of the two hooks 4 being united together integrally (or otherwise) by a preferably flat bar 6, which when the hook 4 is engaged in the eyelet-hole 3 (or 3') is parallel 60 to the under side of the ironing-board *a*, with the outer hook or catch 4 extended outward from the edge of the cover *b*.

c is a cord which when the cover *b* is placed over the board *a*, with its side and end portions 1 and 2 underlapping the same, as seen in Figs. 2 and 3, is passed to and fro across the space between the side portions 1 and hitched onto the opposite outer hooks 4 thereof alternately lacing-wise, and the cord 70 *c* being then pulled taut draws the side edges and adjacent portions of the cover *b* together, when the meeting end portions of the cord *c* are tied or otherwise joined together, as shown in Fig. 2, (or in lieu of the cord *c* an 75 endless cord may be used, if desired.) The end strands of the cord *c*, which extend squarely across the space between the opposite end hooks 4 are then pulled outward and hitched onto the outer hooks or catches 4 of 80 the underlapping end portions 2 of the cover *b*, which causes the latter, with the side portions 1, to be simultaneously drawn toward each other or "stretched," thereby tightening the cover *b* throughout and imparting 85 thereto a perfectly smooth ironing-surface.

d represents cleats, which I preferably interpose between the board *a* and the underlapping side and end portions 1 and 2 of the cover *b* for easing the bearing-pressure of the 90 heads of the hooks 4 on the table 7, (indicated in Fig. 5,) which supports the ironing-board *a*, with its cover *b*, or the cleats *d* may be dispensed with.

By untying, and so releasing the cord *c* 95 from the hooks 4, the cover *b* is easily detached from the board *a*, and by disengaging the hooks 4 from the eyelet-holes 3 3' the cover *b* can be reversed or cleaned or the hooks 4 utilized for other covers.

By my invention an ironing-board is provided over its entire top side with a smooth and compactly-fitting cover which can be made in different sizes according to the size and configuration of the board.

What I claim as my invention, and desire to secure by Letters Patent, is—

An ironing-board cover, having its edges and adjacent portions underlapping the said board at its sides and ends respectively, and having a series of eyelet-holes through the said portions, a hook adapted to be remov-

ably engaged in each of the said holes and connected to an outer hook, and a cord adapted to engage the outer hooks in their assembled position, for drawing the said portions toward each other and tightening the cover to the said board, substantially as described.

In testimony whereof I have signed my

name to this specification in the presence of two subscribing witnesses.

WILLIAM E. HAZARD.

Witnesses:

MARY D. WHITCOMB,
EDWARD W. FURRELL.
